UNITED STATES PATENT OFFICE.

ADOLPH KAUTZKÝ, OF LOS ANGELES, CALIFORNIA.

UNDERGROUND-TROLLEY SYSTEM.

1,034,016.

Specification of Letters Patent. Patented July 30, 1912.

Application filed May 15, 1911. Serial No. 627,221.

To all whom it may concern:

Be it known that I, ADOLPH KAUTZKÝ, a citizen of the United States, residing at Los Angeles, in the county of Los Angeles and State of California, have invented new and useful Improvements in Underground-Trolley Systems, of which the following is a specification.

This invention relates to improvements in underground trolley systems, and it is particularly adapted for street car systems where it is undesirable to use overhead and exposed conductors.

It is an object of the present invention to provide a street car system with conductors arranged below the surface of the street or roadway and in such position that they can be readily reached by a trolley extending downwardly from the car or cars, the conductors being so disposed that water cannot collect about the same so as to make a short circuit at any point.

It is a further object of the invention to arrange a third rail system for cars in which the conductor may be arranged so that all drainage will be carried below the same and out of touch therewith, suitable collecting drains being arranged beneath the roadbed.

It is a further object of the invention to provide an underground trolley system in which a conductor is provided, which affords a practically continuous surface to the trolleys of the cars running over the said system.

In the accompanying drawing forming a part of this specification, Figure 1 is a side elevation of a motor car, the roadbed beneath the same being shown in longitudinal vertical section for illustrating the mounting of the conductor rail and the drain below the same, the section through the roadbed and drain being taken upon the line 1—1 of Fig. 2. Fig. 2 is a transverse sectional view taken through one of the roadbeds and the collecting drain beneath the same. Fig. 3 is a fragmentary detail view showing a preferred form of a trolley employed in connection with the underground system. Fig. 4 is a longitudinal sectional view taken through a road-bed constructed in accordance with the present invention, and the drain beneath the same, the said section being taken upon the line 4—4 of

Fig. 2. Fig. 5 is a plan view of a portion of the roadbed and track constructed in accordance with the present invention, a portion of the roadbed being broken away to show the conductors between the rails, and the arrangement thereof at the switch.

The details of the invention will now be more particularly described, reference being had to the drawing in which—

5 indicates the main rails of a railway system, which are placed parallel in the usual way and are secured to any suitable cross ties as 6. These ties are preferably arranged below the surface of the street or roadway so that the said surface may be brought flush with the tops of the rails as shown in Fig. 2. The ties 6 may or may not be provided with longitudinally extending bearer beams 7 as preferred but it is usual to provide such beams with the present system, since a considerable space is left between the rails 5 and below the ties 6 for the purposes of drainage. The space between the said bearer beams 7 and below the ties 6 is graded and shaped to form a longitudinally extending drain and the surfaces of said drain are generally paved or covered with cement or concrete as indicated at 8 in the drawing. The said drain is depressed at the central portion thereof so as to tend to collect the water as in a gutter, the said drain is graded so that the water may be conducted to suitable points where outlet drains 9 are provided. The said outlet drains may be arranged at as frequent intervals as found necessary, but ordinarily I contemplate employing one of such drains, say in the middle of a city block, and the drain from each cross street as from the positions indicated by the dotted lines 10—10 and 11—11 in Fig. 4 are graded downwardly in opposite directions, and the grades extending toward each other from opposite ends of the block will meet at an outlet drain 9. The drain surface beneath the ties preferably extends from the beams 7 on one side to the beams 7 on the other side so that a moisture collecting surface of ample width is provided below the entire track system. The water collected and running into the space below the rails 5 can thus be carried off in any suitable drain or sewer system.

The conductor for the system may be of

any suitable form but is preferably composed of T rails 12 which are mounted below the surface of the street or roadway and preferably between the rails 5. The 5 said conductor rails 12 are usually supported on insulated bearing plates 13 which are mounted upon the ties 6 and the preferable location thereof with respect to the rails 5 is clearly shown in Fig. 2. The conductor rail is thus supported only upon the ties 6 so that the spaces between the ties are open to prevent any collection of water or moisture near the conductor.

The cars of the system can of course be 15 of any desired type and are provided with a trolley mechanism having a depending trolley pole 14, adapted to extend downwardly from the car or one of its motors as 15 and through a slot 16 preferably formed 20 next to one of the rails 5, the said trolley pole having its lower end bent or turned to one side, so as to extend laterally over the conductor rails 12. The said trolley may be provided with any conductor engaging 25 means as for instance the contact or friction roller 17 as shown in Figs. 2 and 3. The roller is usually made of considerable width so as to be wider than the tread of the conductor rails 12.

30 The central portion of the roadbed is arranged with a street or road surface 18 which extends almost the entire width of the space between the tread portions of the rails 5. A space is left upon one side to 35 form the slot 16 and a slight space as at 19 is also preferably left at the outer side, to accommodate the flanges of the car wheels. The central surface 18 between the car rails is supported at suitable intervals by standards 20 which may be formed of metal and the surface 18 may be secured thereto in any desired manner. The space beneath the standards and beneath one side of the roadbed is preferably filled with concrete, asphalt 45 or other substance, the upper portion thereof of being carried over nearly to the slot 16 so that a firm support is offered to the street surface between the car rails. The said material also forms one side of the conduit for 50 the conductor. The slot 16 in addition to forming an entrance for the trolleys of the cars also affords a drainage space for admitting the water from the surface and into the conduit. The ties having the spaces between 55 them unfilled around the conductor and in the conduit insure the passage of all the water into the drain below the same without coming in contact with said conductor. The trolley may be of any desired type but a 60 simple form is shown in Fig. 3 in which the pole 14 extends into a casing 21 attached to the framing of the motor 15, and having a telescopic movement therein. The upper end of the said trolley pole 14 is usually pro-

vided with a plunger or piston head 22 65 operating in the said casing 21 and a spring 23 normally presses the piston head downwardly so as to keep the trolley in close contact with the conductor rails 12. The broad contact roller 17 is of advantage in that it 70 always insures proper engagement of the rails and the switches in the roadway and the said roller passes readily from the main conductor rail to the switch conductor rail and vice-versa without difficulty. It is an 75 advantage to employ a rail in which the trolley can press upon the upper surface thereof for the reason that switches in the conductor rails are not required and the conductor rails may be brought together at the switches as 80 indicated at 24 in Fig. 5, it not being necessary to leave any space between the same. The trolley bearing upon the upper edges of the said conductor rails, pass readily from the main rail to the switch rails without an 85 interruption of the contact. The trolley will of course be carried with the truck of the car which is guided upon the track by any usual or ordinary switch mechanism as 90 shown at 25. The mounting of the conductor rails upon the insulating plates 13 insures a thorough insulation of the same throughout from the ties and adjacent parts 95 of the system and the return current through the motor is accommodated by the rails 5 of the track.

It will be observed that it is practically impossible to have the rails short circuited by rain or water entering the slots along the track, since the water must immediately fall to the drain along beneath the ties 6. A very large quantity of water can thus be 100 cared for and drained from the tracks without any danger of short circuiting or interference with the operation of the road.

105 The construction of a roadbed in accordance with this system need not be expensive and yet can be made very effective for the purpose of an underground electric trolley system and is thus admirably adapted for 110 use in cities and towns.

What I claim is:

An underground trolley system, comprising 115 a road bed made up of longitudinally extending bearer beams, transversely arranged ties supported by said beams, the ends of said ties extending beyond the outer faces of said beams, rails supported upon said ties directly over said beams and adapted to reach to the surface of the roadway, insulated bearing plates secured to said ties and located a suitable distance from said rails, a conductor mounted upon said plates and extending parallel with said rails, surface supporting standards mounted upon said ties, a street surface section carried by said standards and adapted to overhang said conductor, said street surface section extend- 120 125

ing to the rail at one side of the track and forming a slot at the other side thereof, and a conduit formed between said bearer beams having a depressed central portion, said conduit being inclined toward suitable outlet drains whereby water entering the conduit may be carried away from said conductor.

In witness that I claim the foregoing I have hereunto subscribed my name this 10th day of May, 1911.

ADOLPH KAUTZKY.
